Brisbane, Queensland, Australia

Application February 18, 1931, Serial No. 516,772

13 Claims. (Cl. 122—371)

In a broad sense this invention relates to furnaces for the combustion of solid wet fuels and/or solid wet or dry fuels possessing a high percentage of hydro-carbons generally, and particularly refers to improvements forming parts of the boiler furnace. Fuels high in moisture include saw-dust, megass, tan bark and the like; fuels possessing a high percentage of hydro-carbons in addition to a high moisture content are principally lignites, while bituminous coals, and above all cotton hulls, and the like are representative of fuels conspicuous in their composition for volatile carbons.

Although my improvements may be said to appertain more particularly to the combustion of low grade fuels, they are not necessarily limited thereto. The economic utilization of low grade fuels depends entirely upon furnace efficiency; excessive moisture and/or a high percentage of hydrocarbons in fuel are factors adding materially to the complexity of the combustion problem. With such fuels there are four distinct phases in the process of combustion, namely—
(1) pre-heating of the fuel; (2) evaporation of moisture and its conversion into superheated steam; (3) volatilization of hydro-carbons, their heating to ignition point together with the required quantity of air; and (4) ignition and combustion of both volatile and fixed carbons.

Phases (1), (2), and (3) are preparatory to phase (4), and, their reactions being endothermic, they should be allotted a separate space, preferably away from the boiler. Phase (4), being exothermic should take place in the closest proximity to the boiler, that is in the combustion chamber of the main furnace.

The object of the invention is to provide means for adaption to existing furnaces for the more efficient combustion of the above mentioned fuels, said means comprising apparatus which may be attached to the present boiler furnace, wherein the fuel is passed through the initial or preparatory stages or phases of the combustion process prior to its entrance into the main furnace room.

In order to make clear the character and import of my invention, reference will be made to the accompanying drawing wherein—

Figure 1 is a longitudinal sectional elevation of the apparatus as attached to the boiler furnace;

Figures 2, 3, and 4 are respectively a side sectional elevation, front elevation and horizontal cross sectional plan of the vertical drying grates.

Figure 5 is a view similar to Fig. 1 showing

the modified form of construction in accordance with the present invention.

In Figure 1 the invention is shown in its relation to a boiler furnace, which for convenience is illustrated in chain lines. Two fire grates A and E incline respectively to the front and to the back, and at their apex is mounted a gable C upon steel girders D. Two vertical drying grates B and B' are suspended directly above the gable C, and are spaced apart from each other forming a passage for the fuel, which is fed in at the top. Sliding down between the drying grates B and B' the column of fuel is split into two volumes when approaching the apex of the gable C, and is diverted into opposite directions on to the respective fire grates A and E.

The area of grate A is usually less than that of the main grate E. The relative surface area of these grates can be pre-determined once the analysis of the fuel to be consumed is known; with megass for instance containing fifty per cent of moisture and having a gross thermal value of 3780 B. t. u. per pound, a ratio of one to six should be adopted, as it requires 630 B. t. u. or exactly one sixth of the total heat available to evaporate the contained water and convert it into superheated steam of 600° F., the usual waste heat gas temperature.

The column of fuel, filling the space between the vertical grates B and B', partitions off a portion at the front of the boiler furnace forming a separate chamber not in communication with the main furnace room. Thus the gases resulting from the fire on grate A cannot escape unless they percolate through the column of fuel between the vertical grates B and B'. The percolation of the gases is promoted by the difference in the pressures in the respective fire rooms, that is, the pressure of the gases in the front fire room must exceed that in the back or main fire room by the pressure required to overcome the frictional resistance offered by the wall of fuel. The depth and height of the space between the vertical grates B and B' for a given rate of consumption depends entirely on the nature of the fuel to be burned. With fuels of low density such as wood shavings, megass, cotton hulls and the like, an abundance of natural channels reduces the friction of the gases passing through the column of fuel, consequently the space between the vertical grates can be deeper with low density fuels than with fuels of high density, such as bituminous mine slack.

The vertical grates B and B' are preferably air-cooled, but grate B being exposed to greater

heat may be water cooled instead, in which case it will be connected with the boiler feed system or the boiler itself. These grates B and B' are shown in detail in Figures 2, 3, and 4, and consist of a number of pipes spaced apart, the spacing being dependent upon the texture and divisibility of the fuel. Pipes F of grate B are respectively held by their ends in top and bottom headers G and H, and pipes F of grate B' are held respectively in the top rail K and bottom header I. The ends of pipes F in grate B open into headers G and H. The bottom ends of pipes F in grate B' open into header I, but the top ends are placed in holes in rail K and held in suspension by caps which also close the ends. Air is delivered from a forced draught system into top header G, thence through pipes F of grate B, into bottom header H, thence into bottom header I, the ends of which are connected with the ends of bottom header H by tubes J. From header I the now hot air enters the vertical pipes F of grate B' to be blown out through numerous small holes O which have been drilled in the outer side of the pipes F evenly distributed from the bottom ends to about half way up.

The bottom headers H and I function also as fuel gates between the drying grates B and B' and fire grates A and E, and to enable an unimpeded exit for the fuel, and to progressively advance its subsequent division into two columns, they are located at a distance above the apex of the gable C. The required thickness of the fuel bed on grate E defines this distance.

Short pipes N extend through the header H and furnish the necessary adjustment to the gateway from the drying grates B and B' to the fire grate A. These pipes N are closed at their ends and have holes drilled in them for forcibly distributing the hot air. The construction of vertical grates B and B' enables easy removal and replacement with the least possible interference with the working of the boiler. In the modified form of construction shown in Fig. 5, the feed water line communicates with the lower header of grate B. Feed water flows through grate B in which it absorbs heat and is then led to the boiler P. When the grate B is water cooled, grate B' alone is air cooled.

Since the water vapor driven off from the fuel limits the performance of the combustion apparatus, provision is made in the case of very wet fuel for the separate discharge of the spent gases and the entrained vapors issuing from the upper part of the fuel column. This is effected by placing a partition L across the back compartment which prevents the mixture from following the path taken by the main flue gases; vent M enabling an escape into the atmosphere.

The heat required to pass the fuel through the initial stages of the combustion process is generated by burning a definite portion of the fuel on a separate grate (for example A). This grate A is separated from the main furnace grate E by the intervening vertical grates B and B' which form the approach for the fuel to the fire grates A and E. The resulting gases are distributed over the whole face of the vertical grate B and are forced to traverse the column of fuel, which may be conveniently divided into two horizontal sections or zones to better perceive the effect of the percolating gases upon the mass of fuel. On its passage down between the drying grates B and B' the moving mass of fuel absorbs sensible heat from the percolating gases. In the upper section or evaporation zone this heat sup-

ply is consumed in supporting the evaporation of the contained moisture. The gases leave this section at a comparatively low temperature, the heat absorption in this section being particularly high by reason of the greater head in temperature between the incoming fresh fuel and the heating medium, and also the greater heat absorbing capacity of wet fuel than that of dry fuel.

Diminished in moisture, the fuel enters the lower section or carbonization zone in a semi dry state. The supply of heat being constant, the fuel continues to absorb sensible heat until it reaches the temperature at which carbonization is maintained. Emerging in common with the fire gases the hydro-carbons come into intimate contact with the heated air escaping through the perforations in the pipes forming the back grate.

Thoroughly mixed with the air they travel then in the direction of the draught and are ignited and burned while passing over the incandescent fuel bed on the main grate. Leaving the drying grates B and B' the fuel is passed onto the respective fire grates A and E. It is then in such a state that it will ignite and burn readily producing a high and equable furnace temperature.

The arrangement of placing a partition, such as L, horizontally across the back compartment and immediately above the lower section or carbonization zone, recommends itself where no useful purpose can be served by drawing a mixture of incombustible gases and water vapors of a temperature at or below that of the exit waste gases through the boiler furnace. With extremely wet fuels it is a decided advantage to eliminate so large a volume of inert gases and vapors thus increasing the furnace temperature, and with it the rate and completeness of combustion, which in turn leads to a higher furnace-boiler-efficiency.

The apparatus in itself is totally independent and adapted to be used in conjunction with any type or types of fire-grates, also permitting the application of any known systems of controllable air supply.

As a corollary to the foregoing, and in a broad sense as implied on the first page of the specification, it will be seen that my invention consists essentially of the practical arrangement of improvements as part of the boiler furnace, representing apparatus wherein the fuel passes through the preparatory stages of combustion process enabling the continuous generation of definite, pre-determined volumes of high temperature gases in a separate chamber, their concentration over the whole face of the fuel mass and their subsequent penetration there through resulting in the delivery of dehydrated and/or carbonized fuel in such an advanced state of preparedness on to the fire grate as to insure perfect and complete combustion.

Although the invention has been described and illustrated in relation to the economic combustion of fuels as before mentioned, it will be understood that the invention may be applied to town refuse destructors and the like.

I claim:

1. In furnaces of the class described, a main fire-grate, a subsidiary fire-grate, a vertical fuel delivery chute between said main and subsidiary fire-grates, said chute consisting of water and air tubes, the water tubes being nearest to the subsidiary fire-grate and in communication and in series with the boiler, the air tubes being

- suitably perforated for the delivery and distribution of preheated air for combustion over the fuel bed on the main fire-grate.
2. In a boiler heating furnace of the class described, a main fire-grate and a subsidiary fire-grate, a vertically-arranged fuel delivery chute positioned to deliver fuel in determined proportions to both of said fire-grates, said delivery chute comprising a pair of spaced walls extending across said furnace, one of said chute walls being constructed of tubes through which feed water to the boiler is passed and the other chute wall being constructed of tubes through which combustion supporting air is passed for preheating, and means for causing products of combustion from said subsidiary grate to pass through said chute to pretreat the fuel therein.
3. In a boiler heating furnace of the class described, a main fire-grate and a subsidiary fire-grate, said fire-grates being horizontally spaced and separated by inclined fuel delivery sheds, said furnace having an outlet for the hot gases positioned over the main fire grate, a vertical fuel delivery chute for supplying fuel to both of said fire grates and positioned between said horizontally spaced grates, said chute being formed of two spaced walls extending across said furnace, one of said walls being formed of a plurality of spaced tubes having one end connected to the boiler feed and the other end connected to a supply of feed water, the other of said chute walls being formed of tubes, means for passing cold combustion supporting air therethrough, said chute being positioned so that products of combustion from the subsidiary grate must pass through the column of fuel contained therein in flowing to said outlet.
4. In a boiler heating furnace of the class described, a main fire-grate and a subsidiary fire-grate, said fire-grates being horizontally spaced and separated by inclined fuel delivery sheds, said furnace having an outlet for the hot gases positioned over the main fire-grate, a vertical fuel delivery chute for supplying fuel to both of said fire grates and positioned between said horizontally spaced grates, said chute being formed of two spaced walls extending across said furnace, one of said walls being formed of a plurality of spaced tubes having one end connected to the boiler feed and the other end connected to a supply of feed water, the other of said chute walls being formed of tubes, means for passing cold combustion supporting air therethrough, said chute being positioned so that products of combustion from the subsidiary grate must pass through the column of fuel contained therein in flowing to said outlet, and the chute wall through which air is passed being provided with a plurality of air outlets for supplying combustion supporting air to the contents of the furnace.
5. In a boiler heating furnace of the class described, a main fire-grate, an outlet flue above said main grate, an inclined fuel delivery shed for feeding fuel to said main grate, a vertical fuel delivery chute for supplying fuel to said shed, said chute being removed from said grate and comprising a pair of spaced walls, one of said walls being formed of water tubes connected between a feed water supply and the feed water inlet to the boiler, the other chute wall being formed of air tubes, means for passing air through said tubes, a subsidiary fire-grate positioned below and horizontally spaced from said chute so that the chute is between the subsidiary grate and the outlet flue, and an inclined shed for feeding a portion of the fuel in the chute to the subsidiary grate, the wall of said chute through which water is passed being positioned adjacent the subsidiary fire-grate so that it is first subjected to the hot products of combustion flowing from the subsidiary grate.
6. In a boiler heating furnace of the class described, a main fire-grate, an outlet flue above said main grate, an inclined fuel delivery shed for feeding fuel to said main grate, a vertical fuel delivery chute for supplying fuel to said shed, said chute being removed from said grate and comprising a pair of spaced walls, one of said walls being formed of water tubes connected between a feed water supply and the feed water inlet to the boiler, the other chute wall being formed of air tubes, means for passing air through said tubes, a subsidiary fire-grate positioned below and horizontally spaced from said chute so that the chute is between the subsidiary grate and the outlet flue, and an inclined shed for feeding a portion of the fuel in the chute to the subsidiary grate, the chute wall through which air is passed being provided with a plurality of air outlets for supplying combustion supporting air to the contents of the furnace.
7. In a boiler heating furnace of the class described, a main fire-grate and a subsidiary fire-grate, said fire-grates being horizontally spaced and separated by inclined fuel delivery sheds, said furnace having an outlet for the hot gases positioned over the main fire grate, a vertical fuel delivery chute for supplying fuel to both of said fire grates and positioned between said horizontally spaced grates, said chute being formed of two spaced walls extending across said furnace, one of said walls being formed of a plurality of spaced tubes having one end connected to the boiler feed and the other end connected to a supply of feed water, the other of said chute walls being formed of tubes, means for passing cold combustion supporting air therethrough, said chute being positioned so that products of combustion from the subsidiary grate must pass through the column of fuel contained therein in flowing to said outlet, and the wall of said chute through which water is passed being positioned adjacent the subsidiary fire-grate so that it is first subjected to the hot products of combustion flowing from the subsidiary grate.
8. In a boiler heating furnace of the class described, a main fire-grate, an outlet flue above said main grate, an inclined fuel delivery shed for feeding fuel to said main grate, a vertical fuel delivery chute for supplying fuel to said shed, said chute being removed from said grate and comprising a pair of spaced walls, one of said walls being formed of water tubes connected between a feed water supply and the feed water inlet to the boiler, the other chute wall being formed of air tubes, means for passing air through said tubes, a subsidiary fire-grate positioned below and horizontally spaced from said chute so that the chute is between the subsidiary grate and the outlet flue, and an inclined shed for feeding a portion of the fuel in the chute to the subsidiary grate, the wall of said chute through which water is passed being positioned adjacent the subsidiary fire-grate so that it is first subjected to the hot products of combustion flowing from the subsidiary grate.
9. In a boiler heating furnace of the class described, a main fire-grate and a subsidiary fire-grate, said fire-grates being horizontally spaced and separated by inclined fuel delivery sheds, said furnace having an outlet for the hot gases positioned over the main fire-grate, a vertical

fuel delivery chute for supplying fuel to both of said fire-grates and positioned between said horizontally spaced grates, said chute being formed of two spaced walls extending across said furnace, one of said walls being formed of a plurality of spaced vertical tubes communicating with upper and lower headers, the other of said walls being formed of a plurality of spaced vertical perforated tubes having their upper ends closed and communicating at their lower ends with a header communicating with the lower header of the first-recited tubes, and means for passing air into said upper header to flow down through the tubes connected therewith, through said lower headers, up into the perforated tubes and through the perforations into the furnace.

10. In a boiler heating furnace of the class described, a main fire-grate and a subsidiary fire-grate, said fire-grates being horizontally spaced and separated by inclined fuel delivery sheds, said furnace having an outlet for the hot gases positioned over the main fire grate, a vertical fuel delivery chute for supplying fuel to both of said fire grates and positioned between said horizontally spaced grates, said chute being formed of two spaced walls extending across said furnace, one of said walls being formed of a plurality of spaced vertical tubes communicating with upper and lower headers, the other of said walls being formed of a plurality of spaced vertical perforated tubes having their upper ends closed and communicating at their lower ends with a header communicating with the lower header of the first recited tubes, means for passing air into said upper header to flow down through the tubes connected therewith, through said lower headers, up into the perforated tubes and through the perforations into the furnace, and short perforated tubes depending from the lower header of said first-recited tubes to distribute combustion air in the vicinity of said subsidiary fire-grate.

11. In a boiler heating furnace of the class described, a main fire-grate and a subsidiary fire-grate, said fire-grates being horizontally spaced and separated by inclined fuel delivery sheds, said furnace having an outlet for the hot gases positioned over the main fire-grate, a vertical

5 fuel delivery chute for supplying fuel to both of said fire-grates and positioned between said horizontally spaced grates, said chute being formed of two spaced walls extending across said furnace, one of said walls being formed of a plurality of spaced vertical tubes communicating with upper and lower headers, the other of said walls being formed of a plurality of spaced vertical perforated tubes having their upper ends closed and communicating at their lower ends 10 with a header, and means for passing air through the tubes of at least one of the walls of said fuel delivery chute.

12. In a boiler heating furnace of the class described, a main fire-grate and a subsidiary fire-grate, said fire-grates being horizontally spaced and separated by inclined fuel delivery sheds, said furnace having an outlet for the hot gases positioned over the main fire-grate, a vertical fuel delivery chute for supplying fuel to both 15 of said fire-grates and positioned between said horizontally spaced grates, said chute being formed of two spaced walls extending across said furnace, one of said walls being formed of a plurality of spaced vertical tubes communicating with upper and lower headers and adapted to 20 contain a cooling medium, the other of said walls being formed of a plurality of spaced vertical perforated tubes having their upper ends closed and communicating at their lower ends with a 25 header, and means for passing air through the perforated tubes and through the perforations into the furnace.

13. In a boiler heating furnace of the class described, a main fire-grate and a subsidiary fire-grate, a vertically arranged fuel delivery chute positioned to deliver fuel in determined proportions to both of said fire-grates, said delivery chute comprising a pair of spaced walls extending across said furnace, one of said chute walls 35 being constructed of tubes through which water is passed to the boiler and the other chute wall being constructed of tubes through which a cooling medium is passed, and means for causing 40 products of combustion from said subsidiary grate to pass through said chute to pretreat the fuel therein.

RUDOLF VON MATTEKOVICH.
